FREDERICK B. WALTER, OF WABASH, INDIANA, ASSIGNOR TO B. WALTER & CO., OF WABASH, INDIANA, A CORPORATION OF INDIANA

EXTENSION REFRATORY TABLE

Application filed October 15, 1928. Serial No. 312,731.

The object of my invention is to produce a table, more particularly but not necessarily of the refectory type, wherein the main top-forming sections may be automatically arranged in extension or covering relation with a vertically fixed intermediate extension leaf.

The accompanying drawings illustrate my invention.

Fig. 1 is a plan of the main frame of the top with the ends of the fixed center leaf broken away to show the floating tracks and the guides which support and guide the slides which carry the two main top leaves or table top sections;

Fig. 2 is a vertical section, transversely of the table, of the parts shown in Fig. 1;

Fig. 3 is a plan of the floating slide units and ends of the main top leaves supported thereby;

Fig. 4 an under plan of one of the floating slide units;

Fig. 5 a transverse section of the floating extension sections with one of the floating slide units in elevation;

Fig. 6 a transverse section of one of the floating slide units;

Fig. 7 an elevation of one of the floating slide units associated with its floating track and the support and guide therefor, with the extension sections in extension position relative to the main top;

Fig. 8 a view similar to Fig. 7 with the parts in position where the extension sections have been drawn apart to engage the floating track ready to cause a raising thereof;

Fig. 9 a view similar to Fig. 8 with the extension sections elevated and completely extended;

Fig. 10 a view similar to Fig. 9 with the extension sections moved inwardly to intimate relation covering the main top; and

Fig. 11 a view similar to Fig. 10 with the extension sections moved apart to position ready to lower the floating track sections to drop the extension sections to the plane of the vertically fixed main top.

In the drawings 20 indicates a base frame to be supported by a suitable pedestal or leg structure and carrying a fixed central main top 21 the edges of which overlie the

floating slide units, to be described, the said main top leaf being sufficiently elevated from frame so as to provide room for the necessary vertical movement of the floating slide units and sliding reception of the extension leaves.

At each end of frame 20 are two metal track-and-guide plates 22 and 23. The upper edge of plate 22 is formed into an inclined track 24, two horizontal portions 25 and 26 at opposite ends of track 24 and at different levels, and a stop 27. Similarly, the upper edge of plate 23 is formed into an inclined track 28, two horizontal portions 29 and 30, at the levels of portions 25 and 26, respectively, and a stop 31.

Associated with each pair of plates 22 and 23 is a floating track composed of a pair of connected parallel bars 35, 35 which are spaced apart so that the plates 22 and 23 may lie between them. Arranged between bars 35, 35 near their ends are two rollers 36, 36 which are supported, respectively on the tracks 25—24—26 and 29—28—30, one roller engaging stop 31 when the floating track is in its lowest position and the other roller engaging stop 27 when the floating track is in its upper position. Arranged at intermediate points between bars 35, 35 and between stops 27 and 31, are two rollers 37, 37 so supported that they are exposed slightly above the upper edges of bars 35.

The two extension leaves 40 and 41 are supported by two slide units each of which comprises a middle bar 42 and two slides 43 and 44 slidably associated with bar 42 in a common manner as indicated in Fig. 6. Top leaf 40 is attached to slides 43 at one end thereof and top leaf 41 is attached to slides 44 at the opposite ends thereof. Slides 43 and 44 carry oppositely arranged rack bars 45 and 46 which mesh with a gear 47 journalled on bar 42 so that movement of one slide causes opposite movement of the companion slide. On its under side bar 42 is medially grooved longitudinally, as indicated at 50 to receive the upwardly projecting portions of plates 22 and 23.

Near one end slide 44 is provided, in its face adjacent bar 42, with a pocket 51 in

which is pivoted a pawl 52 having the pin-receiving pockets 53 and 54, pocket 54 being guarded by the guard finger 55. Secured to the under side of bar 42 is a track plate 60 notched at its ends, as indicated at 61, 61 and of such length as to extend between the adjacent edges of plates 22 and 23, notches 61, 61 receiving the stop portions 27 and 31 of said plates.

Projecting inwardly and horizontally from the middle of each floating track is a pin 65 arranged in the plane of pocket 53 of pawl 52 as the free end of said pawl rides upon the upper face of frame 20.

It will be understood from the foregoing description that the extension structure of the table, comprising the two slide units and the connecting leaves 40 and 41, rests upon the floating tracks and is raised and lowered by said tracks and is held against lateral movement, as a whole, by plates 60 which cannot move longitudinally between plates 22 and 23.

The operation is as follows:

With the parts in the positions shown in Fig. 7 the operator pulls outwardly on one of the extension leaf sections 40 or 41 and the two sections move in opposite directions, during this movement the parts reach the position shown in Fig. 8 where pockets 53 of pawls 52 engage pins 65 and proceed to the position shown in Fig. 9, causing the floating tracks to move upwardly along the inclines and the whole unit comprising the extension leaves is thus raised until the leaves 40 and 41 are above the plane of the main top 21. The extension leaf sections 40 and 41 are then moved inwardly until they contact with one another. At the beginning of this inward movement pawls 52 leave pins 65 and fingers 55 cause the pawls to ride over the pins so as to avoid pockets 54. The floating tracks thus remain stationary in their elevated positions.

On the next outward movement of extension leaves 40, 41 pawls 52 ride upon pins 65 until pockets 54 are reached. Return movement of leaves 40, 41 will then cause a return movement of the floating tracks and a consequent raising of the leaves 40 and 41 to the plane of leaf 21. By the time rollers 36 reach track portions 25 and 29 the free ends of pawls 52 contact the upper face of frame 20 and pins 65 descend free from pockets 54 and the parts may be brought to the position shown in Fig. 7.

I claim as my invention:

1. An extension table comprising a vertically fixed base frame and main top carried thereby, a floating top extension structure comprising a pair of oppositely movable extension leaves, inclined tracks interposed between the base frame and floating top, a floating track associated with the inclined tracks, and means connected to one of the

movable top leaves for engaging the floating track to shift it on the inclined tracks only during alternate lateral movements of said leaf.

2. An extension table comprising a vertically fixed base frame and main top carried thereby, a floating top structure comprising two extension leaves, one movable relative to the other, a slide structure comprising three elements one of which is held against longitudinal movement on the base frame and the other two of which are longitudinally movable thereon and each carry one of the extension leaves, vertically inclined tracks carried by the base, a floating track interposed between said tracks and the first-mentioned element of the slide structure, and means connected to one of the movable slides for engaging the floating track to shift it on the inclined tracks only during alternate lateral movements of the extension leaves.

3. An extension table comprising a vertically fixed base frame and main top carried thereby, two pairs of vertically inclined tracks carried by said base, two floating slide units each comprising a central bar and two slides mounted on the central bar, two extension leaves one attached to one slide of each slide unit and the other attached to the other slide of each slide unit, the central bar of each slide unit being interlocked with a track pair against longitudinal movement, a floating track interposed between each track pair and the associated slide unit, and means carried by one of the slides of each unit to engage the adjacent floating track and shift it on its inclined tracks only during alternate lateral movements of a movable leaf, said means comprising a double-notched pawl and cooperating pin, substantially as described.

4. An extension table comprising a vertically fixed base frame and main top carried thereby, two pairs of vertically inclined tracks carried by said base, two floating slide units each comprising a central bar and two slides mounted on the central bar, two extension leaves one attached to one slide of each slide unit and the other attached to the other slide of each slide unit, the central bar of each slide unit being interlocked with a track pair against longitudinal movement, a floating track interposed between each track pair and the associated slide unit, and means carried by one of the slides of each unit to engage the adjacent floating track and shift it on its inclined tracks only during alternate lateral movements of a movable leaf.

5. An extension comprising a vertically fixed base frame and main top carried thereby, a floating top structure comprising an extension leaf, a slide structure supporting said extension leaf, a vertically movable support for said slide structure held against longitudinal movement on the base frame,

vertically inclined tracks carried by the base, a floating track interposed between said track and the slide-support, and means connected to the slide structure for engaging the floating track to shift it on the inclined tracks only during alternate movements of the slide structure.

6. An extension table comprising a fixed top-leaf, a slide-structure mounted beneath said leaf and vertically movable and comprising a horizontally sliding element and a support therefor, and an extension leaf carried by said sliding element, a floating track arranged beneath said slide-structure and movable vertically, and horizontally, inclined tracks supporting said floating track, and means actuated by the horizontally sliding element engaging said floating track to shift the same horizontally only upon alternate strokes in either direction of the extension-leaf carrying element.

In witness whereof I, FREDERICK B. WALTER, have hereunto set my hand at Wabash, Indiana, this 11th day of October, 1928, A. D. one thousand nine hundred and twenty-eight.

FREDERICK B. WALTER.
